UNITED STATES PATENT OFFICE.

HARRY SHOEMAKER, OF PHILADELPHIA, PENNSYLVANIA, ASSIGNOR, BY DIRECT AND MESNE ASSIGNMENTS, TO MARIE V. GEHRING, OF PHILADELPHIA, PENNSYLVANIA, AND INTERNATIONAL WIRELESS TELEGRAPH COMPANY, A CORPORATION OF NEW JERSEY.

WIRELESS-TELEGRAPH SYSTEM.

No. 834,676.

Specification of Letters Patent.

Patented June 26, 1906.

Application filed February 16, 1903. Serial No. 143,729.

To all whom it may concern:

Be it known that I, HARRY SHOEMAKER, a citizen of the United States, residing at Philadelphia, county of Philadelphia, and State of Pennsylvania, have invented a new and useful Improvement in Wireless Signaling Systems, of which the following is a specification.

My invention relates to wireless signaling systems wherein the energy representing the message or signal is of the electroradiant type and transmitted through the natural media.

My invention consists of an arrangement of circuits at the receiving-station of a wireless signaling system whereby greater efficiency in the transmission of signals is obtained.

My invention consists in the employment of a plurality of wave-responsive devices so grouped or arranged as to be individually subjected to the effect of the received energy while they all combine to control a recording-circuit causing an effect in such recording-circuit which is dependent upon the sum of the changes of condition of the several wave-responsive devices.

My invention consists in employing a plurality of wave-responsive devices and joining them in parallel relation with each other so far as relates to the received energy, and connecting them in series in the local circuit controlled by them so that the condition of such local circuit shall be changed by an amount dependent upon the sum of the changes of condition of all the wave-responsive devices.

My invention consists in the employment of a plurality of wave-responsive devices, subjecting each to the received energy, and joining all the wave-responsive devices in series in the same local circuit so that the resistance of such local circuit shall be changed by an amount dependent upon the sum of the changes in resistance of the individual wave-responsive devices.

My invention consists further in the employment of a plurality of separate and distinct receiving-conductors, employing one or more wave-responsive devices in connection with each receiving-conductor, and connecting all the wave-responsive devices in series in the same local circuit, whereby the resist-

ance of such local circuit is changed by an amount dependent upon the sum of the resistance changes of the individual wave-responsive devices.

It often occurs that the wave-responsive device does not invariably respond to the received energy of a wireless signaling system, causing, therefore, an uncertainty in the record of signals. By my system, however, where a plurality of wave-responsive devices are employed, the probability of a false or indistinct record is reduced because it would rarely happen that all of the wave-responsive devices would simultaneously fail to operate. Furthermore, since each wave-responsive device is subjected to the full potential of the received energy each changes in resistance to a considerable extent, and by joining them all in series in the local circuit the ultimate change in resistance in such local circuit is increased.

Where a single conductor or perhaps two or three conductors are employed to receive the transmitted energy because the combined capacity of such conductor or conductors may be relatively small, the charge induced upon them by the transmitted energy is sufficient to maintain their potential sufficiently high to operate a wave-responsive device. If, however, a plurality of conductors be combined it would be found that the potential effected at the wave-responsive device would diminish. In other words, increasing the number of receiving-conductors, so long as such conductors are in direct communication with each other, is not advisable. If, however, a plurality of conductors are employed, and retained separate and distinct with relation to the received energy each will be raised to a like potential which is sufficiently high to operate a wave-responsive device. This arrangement I employ in my system, keeping the receiving-conductors independent from each other, yet causing the wave-responsive devices coöperating with them to operate conjointly to control a local circuit.

Reference is to be had to the accompanying drawings, in which—

Figure 1 is a diagrammatic view of the receiving-circuits in which a plurality of receiving-conductors are employed each communi-

cating with wave-responsive devices in parallel and all the wave-responsive devices connected in series in the local circuit. Fig. 2 is a diagrammatic view of a modified arrangement in which a plurality of receiving-conductors are employed, each influencing a wave-responsive device, and all such wave-responsive devices connected in series in the same local circuit. Fig. 3 is a diagrammatic view of the circuits showing the employment of a single receiving-conductor in conjunction with the wave-responsive devices arranged as in Fig. 1. Fig. 4 is a diagrammatic view showing the employment of a single aerial conductor in conjunction with wave-responsive devices arranged as in Fig. 2.

Referring to Fig. 1 A represents a receiving-conductor of a wireless signaling system, and A' represents a similar conductor. In communication with each aerial conductor are two wave-responsive devices represented by two terminal members bridged by three members 6. Such wave-responsive devices may consist of terminal members of carbon bridged by metallic needles or members resting loosely upon them; or, metallic terminal members bridged by carbon filaments resting upon them. Such devices are self-restoring and though conducting under normal conditions, change their resistance under the influence of received electroradiant energy. The terminal 1 communicates with the lower extremity of the aerial conductor A. Bridging the terminals 1 and 5 are the three needles or filaments 6 forming one wave-responsive device. Similarly, three needles or filaments 6 bridge the terminal 1 and the terminal 4, thus constituting the second wave-responsive device associated with the aerial conductor A. Similarly two wave-responsive devices are associated with the conductor A' and comprise the terminal members 2, 3 and 4 bridged by the needles or filaments 6. Connected between the lower terminals of the wave-responsive devices and the earth-plate E are the condensers K. It is thus seen that each wave-responsive device is connected between an aerial conductor and earth, and that with each aerial conductor are employed two wave-responsive devices connected in parallel relation with each other. The local circuit controlled by these wave-responsive devices comprises telephone receivers R and R', source of energy B, and the four wave-responsive devices connected in series. The path of the current may be traced as follows: From source B through receiver R, conductor 7, terminal 5, needles or filaments 6, terminal 1, needles or filaments 6, terminal 4, needles or filaments 6, terminal 2, needles or filaments 6, terminal 3, conductor 8, and receiver R'. Because of the nature of the wave-responsive devices there is at all times, some current flowing in the local circuit above traced. Upon the reception

of transmitted energy, however, each wave-responsive device changes its resistance and there results a sudden change in resistance in the local circuit depending upon the sum of the changes of resistance of the four wave-responsive devices. This causes a click in the telephone-receivers R, R' thereby recording a signal. For each train of transmitted waves there is produced a click in the telephone-receiver, and a series of trains of transmitted waves will cause a series of clicks in such receiver thereby enabling one to receive code characters. If one or more of the wave-responsive devices should fail to respond to the received energy there would still be recorded a click in the telephone-receivers, because those wave-responsive devices which did respond would change the resistance of the local circuit, and those which did not respond would not operate to prevent the flow of current in the local circuit, because, as previously stated, these wave-responsive devices conduct even under normal conditions. It is seen that the aerial conductors A and A' operate entirely independently of each other, and before oscillations could be communicated from one to the other, such oscillations would be required to traverse and therefore affect two wave-responsive devices. In consequence, each aerial conductor is raised to full potential and such potential is exerted upon the wave-responsive devices.

In Fig. 2, A, A' and A'' represent three independent aerial conductors each communicating with a wave-responsive device of the kind heretofore described. Between the aerial conductor A and the earth-plate E are connected a wave-responsive device comprising terminal members 7 and 8 and the needles or filaments 6, and a condenser K. Between the aerial conductor A' and earth-plate E is connected a condenser K and a wave-responsive device whose terminal members 9 and 10 are bridged by the needles or filaments 6. Between the aerial conductor A'' and earth-plate E is connected a condenser K and a wave-responsive device whose terminal members 11 and 12 are bridged by the needles or filaments 6. To prevent any change of oscillatory energy between the several aerial conductors I employ the choking-coils 13 and 14, which do not, however, prevent the flow of battery-current through the local circuit about to be described. The three wave-responsive devices referred to are connected in series with the choke-coils 13 and 14, the conductors 15 and 16, the receivers R and R', and the source of energy B. The method of operation is the same as that described in connection with Fig. 1, the three wave-responsive devices operating conjointly to control a local circuit.

In Fig. 3 the disposition of the wave-re-

sponsive devices with respect to the local circuit is the same as that described in connection with Fig. 1. However, a single aerial conductor A is employed and by means of a 5 three-leaved condenser C communication is made with the two pairs of wave-responsive devices.

In Fig. 4 the disposition of the wave-responsive devices and choke-coils is the same 10 as in Fig. 2. A single aerial conductor A is employed, and by means of the four-leaved condenser C electrical communication is had with the three separate wave-responsive devices.

15 The arrangement shown in Fig. 1 is my preferred form and though I have described the wave-responsive devices as consisting of metal and carbon elements it is to be understood that I may employ any other form of 20 wave-responsive device.

The wave-responsive device herein described is different from the imperfect electrical contacts such as the filings coherer in that under normal conditions it conducts 25 substantially and does not operate to maintain a circuit in practically disrupted condition. The wave-responsive device herein described, when included in a local circuit, is always conducting considerable electric current, and its contacts must be considered 30 good contacts as distinct from the imperfect contacts.

What I claim is—

1. A plurality of wave-responsive devices 35 connected in parallel with each other, with regard to the means subjecting them to the influence of received energy, and connected in series with each other with relation to a local circuit.

40 2. A plurality of wave-responsive devices, means for subjecting them independently to the influence of received energy, and a local circuit including said wave-responsive devices connected in series.

45 3. In a wireless signaling system, a receiving-circuit, a plurality of wave-responsive devices in parallel with each other in said receiving-circuit, and a local circuit including said wave-responsive devices connected in series with each other.

50 4. In a wireless signaling system, a plurality of independent receiving-circuits, a wave-responsive device included in each circuit, and a local circuit including said wave-responsive devices connected in series.

55 5. In a wireless signaling system, a plurality of independent receiving-circuits, a plurality of wave-responsive devices connected in parallel with each receiving-circuit, and a local circuit including said wave-responsive devices connected in series.

60 6. In a wireless signaling system, a receiving-circuit, a plurality of self-restoring wave-responsive devices connected in parallel with

each other in said circuit, and a local circuit 65 including said wave-responsive devices connected in series.

7. In a wireless signaling system, a receiving-circuit, a plurality of wave-responsive devices connected in parallel with each other, 70 and subjected to the influence of said circuit, and a local circuit including said wave-responsive devices, connected in series.

8. In a wireless signaling system, an aerial conductor, a plurality of wave-responsive devices connected in parallel with each other 75 when subjected to the influence of said aerial conductor, and a local circuit including said wave-responsive devices connected in series.

9. In a wireless signaling system, an aerial 80 receiving-circuit, a plurality of wave-responsive devices connected in parallel subjected to the influence of said circuit, and a local circuit including said wave-responsive devices in series.

85 10. In a wireless signaling system, a receiving aerial conductor, a plurality of wave-responsive devices connected in parallel with each other and associated with said aerial conductor, and a local circuit including said 90 wave-responsive devices connected in series with each other.

11. In a wireless signaling system, an aerial conductor, an earth connection, and a plurality of wave-responsive devices connected in parallel with each other and between said aerial conductor and earth connection, and a local circuit including said wave-responsive devices connected in series with each other.

95 12. In a wireless signaling system, an aerial conductor, an earth connection, a plurality of wave-responsive devices connected in parallel with each other and connected to separate condensers between said aerial conductor and earth connection, and a local circuit including said wave-responsive devices connected in series with each other.

13. In a wireless signaling system, an aerial conductor, an earth connection, a plurality of wave-responsive devices connected in parallel with each other between said aerial conductor and earth connection, a condenser in each branch circuit including a wave-responsive device, and a local circuit 110 including said wave-responsive devices connected in series with each other.

115 14. In a wireless signaling system, a plurality of aerial conductors, a plurality of wave-responsive devices connected in parallel with each other and associated with each aerial conductor, and a local circuit including all said wave-responsive devices connected in series with each other.

120 15. In a wireless signaling system, a plurality of aerial conductors, a plurality of branch circuits associated with each aerial conductor and each including a wave-respon-

sive device and condenser, and a local circuit including said wave-responsive devices connected in series with each other.

16. In a wireless signaling system, a plurality of independent aerial conductors, an earth connection, a plurality of wave-responsive devices associated with each aerial conductor, a condenser connected between each wave-responsive device and earth connection, and a local circuit including said wave-responsive devices connected in series with each other.

17. A wireless signal-receiving system comprising a plurality of wave-collectors, a single indicating mechanism and a plurality of wave-responsive devices in parallel for the passage of the signal-transmitting waves and in series in the circuit of the indicating mechanism.

18. A wireless signal-receiving system comprising a plurality of wave-collectors, and wave-responsive devices, a single indicating mechanism, and means for cumulating the effect of the signal-wave upon the different wave-responsive devices in the action upon the indicating mechanism.

19. A wireless signal-receiving system comprising a local circuit, an indicating mechanism therein, a plurality of wave-responsive devices in series in said local circuit, and a plurality of wave-collectors each acting upon one only of the wave-responsive devices.
